UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

THREAD-PARTING MECHANISM FOR LOOMS.

No. 897,404.

Specification of Letters Patent.

Patented Sept. 1, 1908.

Application filed November 16, 1907. Serial No. 402,398.

To all whom it may concern:

Be it known that I, ALONZO E. RHOADES, a citizen of the United States, and resident of Hopedale, county of Worcester, State of Massachusetts, have invented an Improvement in Thread - Parting Mechanism for Looms, of which the following description, in connection with the accompanying drawing, is a specification, like letters on the drawing representing like parts.

This invention relates more particularly to automatic looms wherein the running filling is replenished prior to complete exhaustion, and to the mechanism for parting the old filling-end near the shuttle, such filling-end extending from the cloth to the shuttle containing the filling-supply or bobbin about to be abandoned.

In United States Patent No. 683423 granted September 24, 1901 to C. H. Draper mechanism is provided to clamp the old filling-end and part it near the shuttle, the clamped end then being drawn forward to bring it into range of the temple thread-cutter so that the latter may sever the end close to the cloth. The clamping of the filling-end was positive, and in order to prevent breakage of the end when the parting and clamping mechanism returned to normal position means were provided in said patent to move such mechanism in a diagonal path toward the edge of the cloth, thereby relieving the clamped end from strain and preventing breakage.

My present invention has for its object the production of novel means for effecting the movement of the clamping and parting mechanism toward the cloth after the old filling-end has been parted and while it is clamped.

The clamping and parting means is mounted on the shuttle-feeler, and I have also so constructed and arranged the apparatus that the feeler moves completely across the mouth of the replenishing box when the shuttle is properly positioned therein for replenishment.

The various novel features of my invention will be fully described in the subjoined specification and particularly pointed out in the following claims.

Figure 1 is a transverse section, on the line 1—1, Fig. 2, of a sufficient portion of a loom, with my present invention applied thereto, the shuttle-feeler, and the means for

clamping and parting the old filling-end, being shown in normal inoperative position; Fig. 2 is a top plan view of the mechanism illustrated in Fig. 1, but with the lay farther forward; Fig. 3 is a view similar to Fig. 1 but showing the feeler in operative position across the mouth of the replenishing shuttle-box, and just before the clamping and parting means is operated; Fig. 4 is a front elevation of the feeler, the carrier on which it is mounted, and the controller to govern lateral movement of the feeler, said controller being in section; Fig. 5 is a detail in front elevation of the inner end of the replenishing shuttle-box; Fig. 6 is a detail of the setting device, to be referred to.

Referring to the drawings, the lay A¹, having its raceway transversely recessed at a adjacent the mouth of the replenishing shuttle-box B, the transference f' Fig. 1, fulcrumed at f and adapted to remove the filling-carriers or bobbins b^x from the filling-feeder F, (partly shown in Fig. 1) and the controlling rock-shaft d', may be and are of well known construction.

Herein I have shown the back wall b of the shuttle-box B as provided with an upright opening b', Fig. 5, in line with the recess a, the top plate b² being extended over such opening, the purpose of the latter being to receive the extremity or tip of the shuttle-feeler when the shuttle S is properly boxed, so that the feeler can extend completely across the mouth of the box, as shown in Fig. 3, and carry the opening between the cutting blades as close as possible to the plane of the back wall of the box, to hold the thread securely trapped when the blades are closed.

In the present embodiment of my invention a bracket 1 on the loom side has a horizontal, inwardly extended stud 2 on which is mounted the hub 3 of a rather short upturned arm or carrier 4, shown in Fig. 4 as slightly bent laterally and having its upper end enlarged to form a boss 5, carrying a stud 6 at right angles to the stud 2. Upon this stud is fulcrumed the enlarged and flattened end 7 of an inclined, upturned shank 8 terminating in a rearward extension constituting the shuttle-feeler 9. The face of the boss 5 forms a broad, flat and firm bearing support for the flattened end 7 of the shank, the feeler being movable bodily in a fore and aft direction with the carrier 4 and

also being adapted to swing or rock relatively thereto upon the stud 6 as a fulcrum, as will be manifest. An upturned lug or follower 10 on the feeler travels in an inverted trough-like cam or controller 11, rigidly secured to the breast-beam A⁴⁰, the controller being curved in the direction of its length, Fig. 2, and it is also curved or arched slightly in side elevation, Figs. 1 and 3.

10 Referring to Fig. 2 it will be seen that the groove in the controller is substantially at right angles to the lay at its rear end, as at 11^x, (see dotted lines) so that the final movement of the feeler across the lay will be in a direct line and straight across the mouth of the shuttle-box.

When filling-replenishment is called for the carrier 4 is swung rearward on its fixed fulcrum 2 to the position shown in Fig. 3, and it 20 carries the feeler with it, but as the follower 10 travels along the cam-like controller 11 the feeler will be moved laterally on its fulcrum 6 from its normal, inoperative position shown in full lines, Fig. 2, into position directly opposite the recess a on the lay and the opening b', as in dotted lines Fig. 2. Thus the feeler is moved away from the edge of the cloth as it is moved to operative position, and upon return movement the reverse 30 action is effected, the feeler moving toward the edge of the cloth, for a purpose to be explained hereinafter.

The swinging movement of the carrier may be effected by any desired means, and 35 herein I have shown a pin 12 on the carrier extended between jaw-like members 13, 14 controlled by a spring 15 and moved operatively by the rock-shaft d' when the latter is turned to effect the operation of the 40 replenishing mechanism, as in United States Patent No. 846700 granted March 12, 1907 to Smith and Stimpson.

Upon the feeler 9 I mount suitable means to clamp and part the old filling-end when the 45 feeler is operatively positioned as described, and I have chosen for illustration means for the purpose substantially as shown in United States Patent No. 834269 granted October 30, 1906 to Cunniff.

50 The tip of the feeler 9 is notched at 9^x to receive the filling-thread when the feeler is moved into operative position as shown in Fig. 3, the upper and lower edges of the notch being shown as flared, to better direct the 55 thread to the cutting blades, the fixed blade 16, see dotted lines Fig. 3, being secured to the feeler adjacent the lower edge of the notch, while the movable blade 17 is fulcrumed on the stud 18, and cooperates with 60 the blade 16 to part the thread while cooperating with the plate 19 which constitutes the fixed member of the clamp, as in the Cunniff patent referred to. The movable member 17 is thus a part of the clamp and also a 65 part of the means for parting the filling, its

heel 20 being struck by the advancing lay, to first clamp the filling-end and then to part it at the side toward the shuttle, the end remaining clamped when the feeler returns to normal, inoperative position, Fig. 1. But 70 during such return movement the feeler is moved toward the edge of the cloth, as has been explained, and the thread clamp is moved with it, so that the strain upon the thread is slackened and danger of breakage 75 is obviated, the clamped thread end being moved into position to be engaged by the usual temple thread-cutter, not shown.

By reference to Fig. 3 it will be seen that when the lay strikes the heel 20 to close the 80 blades, to successively clamp and part the thread, the notched tip of the feeler is extended through the opening b' in the back wall of the box, and the extremities of the blades 16 and 17 project rearward slightly 85 beyond the plane of the front face of said back wall. As a result the thread to be parted is trapped in what is practically a closed space, for it crosses the opening b' and between the edges of the blades and hence 90 cannot escape when said blades are closed, as the box wall holds the thread from rearward movement and the blades prevent it from moving up or down, or forward, out of the opening between their edges. 95

As the clamping and parting device is closed when the feeler is in normal position such device must be set or opened before it is operatively positioned to coöperate with the old filling-end, and herein the setting 100 device is mounted on a bracket 21 depending from the controller or cam 11, the bracket having pivoted to it at 22 a short arm 23, Fig. 6, provided with a cam rib 24. A spring 25 acts to maintain said rib in lifted position, 105 the spring being shown in dotted lines Fig. 6, a stop pin 26 limiting upward movement of the arm 23. A lateral pin 27 on the heel of the movable member 17 of the thread clamp and parter is adapted to pass under the rib 110 24 as the feeler moves rearward to operative position, the rib then acting to swing the member 17 into open position. After the clamp has been closed the pin 27 wipes over the top of the rib 24 as the feeler returns to 115 normal position, the arm 23 being swung downward against the action of spring 25 as the pin 27 passes over the rib, so that no opening movement of the clamp is effected. This setting device in its general construction 120 is substantially the same as shown in the Draper patent No. 683423 referred to.

So far as my present invention is concerned the particular mechanism for clamping and parting the old filling-end may be of any desired character and construction, that shown herein being for purposes of illustration; and so, too, the means for swinging the carrier on which the feeler is mounted may be changed.

Having fully described my invention, what 125

I claim as new and desire to secure by Letters Patent is:—

1. In an automatic filling-replenishing loom, a swinging carrier, a shuttle-feeler pivotally mounted thereon and laterally movable relatively thereto, means carried by the feeler to clamp and part the thread of the filling-supply to be abandoned, and means to control the lateral movement of the feeler 10 and cause it to move toward the edge of the cloth as the carrier returns to normal position after replenishment, to prevent breakage of the clamped end of filling.

2. In an automatic filling-replenishing 15 loom, a swinging carrier movable rearwardly prior to filling replenishment, a shuttle-feeler pivoted on the carrier to rock laterally and also to move bodily with the carrier, a controller to govern the lateral movement of the feeler and cause it to approach the edge of the cloth as the carrier returns to normal position, and means mounted on the feeler to clamp and part the thread of the filling-supply to be abandoned, the combined 20 rearward movement of the carrier and the lateral-rocking of the feeler operatively positioning said means to act upon the thread.

3. In an automatic filling-replenishing 25 loom, a lay having a shuttle-box, a swinging carrier, means to move it toward the lay when replenishment is called for, a shuttle-feeler pivotally mounted on and movable with the carrier and also laterally relatively thereto, to cross the mouth of the shuttle-box when the shuttle is properly boxed, a fixed controller cooperating with the feeler, to govern its lateral movement when moved forward or back by the carrier, and means on the feeler to clamp and part the thread of the 30 filling-supply to be abandoned when replenishment is effected, the controller causing the feeler to move laterally toward the edge of the cloth when the carrier returns to normal position, to prevent breakage of the clamped 35 end of filling.

4. In a loom, automatic filling-replenishing mechanism, a lay, a shuttle-box thereon at the replenishing side having an opening in

its back wall adjacent the mouth of the box, 40 a shuttle-feeler, thread parting means thereon, and means acting automatically when replenishment is called for to move the feeler into position to cross the mouth of the shuttle-box and enter the opening in its back wall when the shuttle is properly boxed, to 45 thereby cause the parting means to extend across the plane of the back wall and trap the thread to be parted.

5. In an automatic filling-replenishing 50 loom, an upturned, swinging carrier, means to move it rearward when replenishment is called for, a shuttle-feeler pivotally mounted on the carrier, to move bodily therewith and also laterally relatively thereto, a fixed cam to govern the lateral movement of the feeler, 55 a follower on the latter coöperating with the cam, means on the feeler to clamp and part the thread of the filling-supply to be abandoned, and a device mounted on the cam to set the clamping and parting means when 60 the feeler is moved into operative position, the cam acting, upon return of the carrier to normal position, to move the feeler toward the edge of the cloth.

6. In an automatic filling-replenishing 65 loom, means bodily movable in a diagonal path, upon filling replenishment, to act upon and clamp and part the thread of the filling-supply to be abandoned, return of said means to normal position toward the edge of the 70 cloth preventing breakage of the clamped end of filling, combined with a support for said means, comprising two pivotally connected members one of which is adapted to swing automatically in a path parallel to the 75 edge of the cloth and the other transversely to the path of movement of the first member, and means to control the transverse movement of the second member.

In testimony whereof, I have signed my 80 name to this specification, in the presence of two subscribing witnesses.

ALONZO E. RHOADES.
